GARMENT HANGER

Gerald Massa and James Demola,
Staten Island, N. Y.

Application March 20, 1953, Serial No. 343,592

5 Claims. (Cl. 223—89)

1

Our invention relates generally to improvements in garment hangers and has reference particularly to a garment hanger which may be extended to accommodate wearing apparel of various weights and sizes.

An object of this invention is to provide a garment hanger, which embodies separate extensible arms carried by the hanger proper, and which allows the arms to be extended or retracted to any desired degree, and provides means for holding each arm in any of its adjusted positions.

A further object of the present invention is to utilize a light plastic material as the substance from which to construct a hanger of this character, and thereby benefit from the sturdy qualities of such material to afford adequate support for almost any weight of garment.

A still further object of the invention is to provide a novel means of mounting the extensible arms upon the body of the hanger, whereby the arms are separately and readily adjustable and securely held in any of their relative positions.

We accomplish these and other objects of this invention by means of the novel features of construction and combination of parts, described in the following specifications, set forth in the appended claims and illustratively exemplified in the accompanying drawing, in which:

Fig. 1 is a front elevational view of my improved garment hanger showing the extensible arms in retracted position;

Fig. 2 is a top plan view of one end or wing portion of the hanger showing an arm in extended position as indicated in dotted outline in Fig. 1;

Fig. 3 is a substantially transverse sectional view taken on lines 3—3 of Fig. 1;

Fig. 4 is an enlarged front elevational view of one side or wing portion of the hanger, illustrating the extensible arm in projected position.

Referring now to the details of construction, 10 denotes a garment hanger molded or stamped in a single piece of plastic or other suitable material, comprising a substantially triangular shaped frame consisting of an arched upper portion 11 of flat cross section forming a pair of straight-edged wings and having an upright hook 12 projecting from the apex of the arch, and a connecting bar 13 running between the outer ends of the wings of the arched portion 11 to form the base of the triangular member. This construction is in common use in the field of garment hangers.

2

According to the present invention, the arms or wings of the arched portion are used to support the extensible straight-edged arms 14, which are flat lengths of material, the same or similar to that of which the hanger proper is made, and which are designed to lie flat against one face of the arched portion 11, as illustratively exemplified in Figs. 2 and 3.

The arms 14 are symmetrically identical, and 10 each is provided with an elongated smooth sided rectilinear slot 15 extending from what may be termed its inner end and closely adjacent the apex and parallel to the straight-edged upper side thereof, to a point substantially midway of 15 the length of the arm itself. A second slot 16 is arranged in each arm 14 and consists of three arcuate shaped openings 17 arranged in spaced succession beginning near the outer end of the slot 15 and disposed adjacent the mid portion 20 of the arm and ending at the outer end of the latter, the arc of each portion 17 of slot 16 being disposed downwardly and towards the outer end 25 of the arm to open into the midportion of the forward portion 17 of the next arc, as illustrated in Figs. 1 and 4, the outermost arc 17 terminating in an upturned closed end 18 at an elevation corresponding to that of each of the inner closed ends 18 of the arcuate portions 17. A guide button or peg 19 is mounted in each arm or wing 30 of the arched portion 11 of the hanger 10 adjacent the bottom side and approximately midway the length of the said wing. The button or peg 19 projects through the slot 15 and is provided with a head 20 to prevent the extensible arm from separating from the adjacent wing of 35 the arched portion 11, while allowing the arm to move parallel thereto while permitting pivotal movement of the arm 14 about the peg 19. A second button or peg 21 is mounted adjacent the outer end of the wing of the arched portion 11 and in the vicinity of the upper corner thereof to project through the slot 16 and to prevent removal of the arm 14 by means of a head portion 22. The pegs 19 and 21 are permanently secured 40 in the hanger wings by means of cement or other fastening means.

According to this construction, each arm 14 is independently adjustable to an extended position by swinging the arm upwardly about the pivot peg 19 until the peg 21 is in the lower portion of 50 an arcuate opening 17 at which position the arm 14 may be freely extended beyond the end of the adjacent wing of the arched portion 11 of the hanger 10. When the proper position is reached 55 and the arm 14 is swung downwardly over the

portion 11, the peg 19 will be at some point intermediate the ends of slot 15 and the peg 21 will have seated against the upper closed end of one of the arcuate openings 17 constituting slot 16. Thus the arm 14 is held against outward movement by the position of the peg 19 in the upper closed end of the opening 17 and against rotary movement about peg 21 by the peg 19 in the slot 15, the arm 14 being held against the corresponding wing or arm of the hanger by the heads 20 and 22 of the pegs which overlap the sides of the slots 15 and 16. In a similar manner each arm 14 may be returned to its initial position as illustrated in Fig. 1.

It should be noted that the weight of each of the arms 14 tends to pivot the arm about peg 19 in a direction to lock the arm by pressing the rounded end 18 of one of the arcuate slots 17 into engagement with the other peg 21. This locking action will be enhanced by the weight of a garment supported on the hanger. Moreover, the direction of extension of the arms 14 is parallel to the straight-edged upper surfaces of the arched portions 11 of the hanger and also to the straight-edged upper surfaces of the arms 14 whereby the straight-edged upper surfaces of the arched portion 11 and of the arms 14 are maintained substantially in alignment so that the slope of the shoulder portions of a garment supported by the hanger will always be maintained at the correct angle. Additionally, it should be noted that there are no gaps or irregularities in the upper surface of the hanger in any position of extension of the arms.

Having now described our invention in detail and the manner in which the same operates, what we claim and desire to secure by Letters Patent is:

1. In a garment hanger, the combination with a body portion comprising a triangular frame forming oppositely projecting wing portions, of arms adjustably associated with the wing portions to increase the effective length thereof, each arm having two longitudinally extending spaced slots formed therein, one thereof being an elongated rectilinear opening extending outwardly from the inner end portion of each arm, the other consisting of a plurality of successive upwardly extending arcuate openings communicating with each other at their lower ends to form a continuous passage in the outer portion of each arm, and spaced pegs projecting from each wing portion to respectively enter said slots in each arm, whereby the latter may be moved transversely of the pegs by pivoting said arms about the pegs in the rectilinear openings and allowing the respective other pegs to seat in selected ar-

cuate openings to hold the arms fixedly longitudinally positioned with respect to said wings.

2. An adjustable arm for each wing portion of a garment hanger, as claimed in claim 1, in which each peg consists of a shank portion permanently mounted in the wing and a head portion overhanging the walls of the respective slots to allow longitudinal adjustment of the arms on the wing portions but holding the arms against separation from the latter.

3. An adjustable arm for each wing portion of a garment hanger, as claimed in claim 2, in which each of the arcuate openings in the arms is formed with an upwardly directed closed end portion curved to form a seat for the respective peg, and wherein the sides of the rectilinear slot are smooth.

4. A garment hanger of the class described, comprising: a central arched portion including a pair of laterally extending wing portions having straight-edged upper surfaces; a pair of symmetrically arrangeable extensible arms having straight-edged upper surfaces parallel to said straight-edged upper surfaces of each of said wings having an elongated rectilinear slot formed therein and extending parallel to said straight-edged surface of said arm outwardly from the inner end portion of each arm and a plurality of upwardly extending arcuate slots formed therein outwardly of each rectilinear slot, each arcuate slot terminating in an upwardly directed closed end portion, the lower ends of said arcuate slots intercommunicating with each other to form a continuous passage in the outer portion of each arm; a first pair of pegs carried by said wings and movably engaging said rectilinear slots; and a second pair of pegs carried by said wings and positioned outwardly with respect to said first pair of pegs, said second pair of pegs being movable in said arcuate slots, whereby said arms may be extended outwardly and fixedly positioned against outward movement with said second pegs in engagement with any desired ones of said closed slot end portions.

5. A hanger according to claim 4, wherein said pegs and said slots are so positioned that said straight-edged portions of said wings and said slots are maintained substantially in alignment in all fixed positions of adjustment of said arms.
